UNITED STATES PATENT OFFICE.

IRENE HAMMOND STOLL, OF CLEVELAND, OHIO.

HAIR DYE.

1,405,458.

Specification of Letters Patent. Patented Feb. 7, 1922.

No Drawing.

Application filed January 28, 1919. Serial No. 273,642.

To all whom it may concern:

Be it known that I, IRENE HAMMOND STOLL, a citizen of the United States, residing at 2625 E. 51st Street, city of Cleveland, 5 in the county of Cuyahoga and State of Ohio, have invented a new and useful Improvement in Hair Dyes, of which the following is a specification, the principle of the invention being herein explained and the 10 best mode in which I have contemplated applying that principle, so as to distinguish it from other inventions.

My invention relates to a hair dye and more particularly to a fluid compound especially adapted to improve the dyeing of live hair.

I have learned that other hair dyes left something to be desired, either in respect to their deterioration, obtaining of fast colors, 20 precise shades, rapidity of result or injurious effects upon the scalp. Sugar of lead is dangerous to sore scalps. Some dyes heretofore used, after a certain lapse of time threw off decidedly queer shades so grotesque in 25 fact as to be intolerable. Others would not permit washing of the head for twelve hours afterwards. Besides, some previously marketed dyes have included ingredients which were difficult to procure or were monopolized 30 in one way or other by foreign interests.

Hair is very much more difficult to dye than textile fabrics, because it is less readily penetrated. This is especially true of straight, hard and wiry hair, from which 35 the dye is easily stripped by friction, or removed by the natural oil of the head.

My hair dye is being sold in three two ounce bottles, each containing a different solution and visually characterized by their 40 distinct colors; one being red, another blue and the third either pale yellow or pale green. One set of three solutions, including the red, the blue and the green, is for black and all the dark brown shades. The other 45 set, including a red, a blue and the pale yellow is for light brown, blonde and reds. To obtain a chestnut color, medium brown, drab and auburn shades a combination of the ingredients of the green and pale yellow 50 solutions may be used. In order to secure red shades add ten grains and up of sodium

sulphide to the pale yellow solution. The various shades may be produced with each set of the triple colored solutions by varying the number and proportion of the ingredients of each. The corresponding solutions of each set vary slightly in the proportion of the ingredients and in some instances have one or more ingredients added or omitted.

Human hair may be divided into three classes, namely, fine quality, medium quality and coarse quality and each requires different treatment.

The three solutions may be successfully applied in any order, but I have discovered that quickest results are obtained in the case of soft fibres by following this order, namely; red, yellow or green and then blue. The best results for soft fibre are, however, 70 obtained in the following manner; first apply the red and allow it to dry, next the blue and allow it to dry and finally the yellow or green. The red constitutes the base color upon which the other two act. The blue 75 drives the red in and forms the set for a natural hair color. The green sets and darkens the blue and red base upon the hair, finally giving the color and bringing the alkalies up to the surface and thereby leaving 80 a permanent shade upon the hair. As a result of the rising alkalies a sediment is left, which must be rinsed off. For hard fibered hair I have discovered it best to apply the solutions in this order, yellow, blue 85 and red but in doing so the operator must be careful of undesirable results due to the likelihood of a chemical action occurring on the brush when first dipped in the red solution. To avoid this it is better to clean the brush 90 prior to dipping it into the red solution and even then to bring it to the head as quickly as possible. For very tough fibered hair the blue solution may be advantageously modified so as to contain a little less ammonia 95 and a little more vitriol.

In order to afford opportunity to make comparison between the formulæ of different sets of three solutions each depending upon the group of shades which it is possible to 100 obtain therewith I will give the formulæ for two sets. The first set comprises the three

distinct green, blue and red solutions and the second set includes the pale yellow, blue and red solution triad.

5 *Set for darker shades.*

- Green solution.—16½ grams of copperas dissolved in 2 oz. of plain water; 25 grains of burnt blue vitriol dissolved in 3 drams of water and ½ drachm of ammonia. Add 10 blue vitriol solution to copperas solution, then filter; to filtered solution add 3 grains of zinc oxide. Then add 10 grains of burnt soda to filtered solution, shake well until soda dissolves; then filter again. To filtered solution add 25 grains of copperas, 3 grams of sal ammoniac and 2 grains of cream of tartar, then dissolve.

- Blue solution.—50 grains of burnt soda dissolved in 1 oz. of water and a little ammonia. To above solution add 75 grains of burnt blue vitriol and 5 drams of ammonia, then add 1½ drams more of plain water to make 2 oz. and two grains of citric acid.

- Red solution, (blacks and dark browns).—25 2 grams of pyrogallic acid (extract of log wood) dissolved in 1 oz. of water; ¼ of an oz. of peroxide; 25 drops of acetic acid; 2 grams of salt petre.

30 *Set for lighter shades.*

- White solution.—Dissolve 4 grams of copperas (green, whitish salt) in one ounce of water; add to this 1½ grams of salt petre; add 2 drams of peroxide; add 2 drams of ammonia; add 7 more drams of water and filter. After filtering add 2 grams of sal ammoniac, 2 grains of cream of tartar to prevent settling.

- Blue solution.—50 grains of burnt blue vitriol dissolved in 1 oz. of water. Add 8 drams of ammonia, 2 grams of burnt soda; 2 grams citric acid.

- Pyro or red solution.—1 gram of Pyrogallic acid; 1½ oz. of water; ¼ oz. of peroxide; 15 drops of acetic acid; 10 grains of salt petre.

I have discovered the following to act as equivalent ingredients:

- For copperas, iron alum or iron protosulfate.

For ammonia, sal ammoniac with caustic soda.

For zinc oxide, zinc dust, zinc sulphate or aluminum sulphate.

- 55 For burnt soda, soda ash, baking soda, sal soda, sodium hydroxide, quick lime, unslacked lime, caustic potash, potash or common salt.

- For sal ammoniac, nitrate ammonia or ammonium sulphate.

For cream of tartar, citric acid.

- For pyrogallic acid, tannic acid, malic acid, logwood, henna or alcohol with peroxide, sodium sulphide, carbide or acetanilide.

For acetic acid, citric acid, glycerine, formic acid or tartaric acid.

For salt petre, alum, burnt alum or potash.

For sodium sulphide, common salt or 70 Glauber salt.

For blue vitriol, copper acetate or binitrate.

The hair and scalp should both be first thoroughly washed to remove all dirt, oil 75 and scales. After the dyeing operation, which in practice is usually carried out by means of a soft short bristled tooth brush, the head and hair should be again washed with a soapy solution containing a measure 80 of salt and thereafter rinsed in a weak saline solution.

Previous hair dyes, so far as my knowledge extends, have been either a one or two bottle variety. The one bottle dyes are 85 excessively slow because about fourteen successive applications are necessary. They were usually applied about twice daily. The two bottle dyes were quicker. The first coat being to lend color and the latter application or coats being proposed to drive 90 in the color. I believe I may be the first to employ a three solution hair dye.

The broad principle of dyeing anything comprehends three steps, namely, to clean, 95 to apply a mordant and finally to dye. The cleansing ingredients which I employ likewise cut any grease or oils on the hair or scalp and may be salts of ammonia and alkalies; the mordants may be organic acids 100 and sulphates of iron; the dyes may be inorganic salts of copper and wood extracts.

Green solution.—The dissolved blue vitriol in water plus ammonia added to copperas dissolved in water causes a sediment 105 which must be filtered because such sediment counteracts the action of the zinc oxide and burnt soda, which is later added to first filtered fluid; by causing an action which throws up more sediment and further filtering. Then to green filtered fluid add sal ammoniac for setting color, also add enough copperas to make up enough for the amount lost in the treating of green solution. Add enough cream of tartar to 115 prevent the last filtered fluid from settling. The soda and sal ammoniac as added above tend to eliminate the blue black and brings out a browner black which more closely approaches a natural color. This green fluid with more ammonia added to blue fluid as well as the addition of more peroxide of hydrogen and salt petre to red solution, achieves darker browns. The green solution is caused by an additional amount of 120 copperas and blue vitriol (burnt white.)

It is advisable to have burnt soda powdered very fine and well shaken for about one-half minute. Filter a second time because it must be rapidly dissolved to produce a 125

quick action before too much sediment is thrown up. If there is delay too much sediment will be removed.

Blue solution.—The red and blue solutions make a direct brown which must be darkened or blackened and set, and finished by green solution if it is an average texture of hair. If, however, it is a hard, or very hard fibre (meaning exceedingly wiry) 10 more applications than one must be made putting blue solution on first and allowing each fluid to dry before applying next. Burnt sal soda helps to set and enrich the color also will prevent blue black by 15 adding more peroxide in red solution. Burnt blue vitriol causes the brown blacks also counteracting blue blacks and off shades. The burning of blue vitriol causes it to lose three-fourths of its inactive 20 ingredients and increases its solubility thereby requiring less ammonia and correspondingly concentrating. Used with ammonia helps to set color. Less ammonia and more water is used to prevent the crystallizing of 25 green solution and stops stripping or cracking. Citric acid is used to neutralize action of green solution and blue solution beside adding gloss to acetic acid in red solution. The blue color results from the action of 30 ammonia and burnt blue vitriol.

Red solution.—Pyrogallic acid gives the shades, water the body, peroxide helps to drive the color in, acetic acid gives gloss and acts on the alkalies in the blue solution, 35 helping to set. Salt petre slightly attains a reddish brown and acts with peroxide and ammonia. Sediment of red solution occurs 12 hours later after mixing. Have learned by experiment that it helps to set, and soapy 40 water plus one tablespoon of salt powdered over head after drying, then a clear rinse plus a tablespoon of salt removes all sediment and dullness, also causes stimulation to hair roots and helps to set.

Blue solution.—More or less burnt blue vitriol plus ammonia plus burnt soda causes the various shades of browns to blondes. Burnt blue vitriol varies the shades. Burnt 45 soda enriches a shade and sets. Ammonia helps to effect and "set" and acts on pyrogallic acid.

Red solution.—Pyrogallic acid causes different shades modified according to the amounts used. Peroxide drives the pyrogallic acid in. Acetic acid furnishes a gloss while salt petre varies the shades of reds and auburns.

Yellow solution.—Salt petre, or sometimes sal ammoniac or soda used with copperas, 50 dissolved in water to which an excess of ammonia and peroxide is added and by taking the dark or resulting fluid and filtering, gives the yellow fluid. This is used to give the blue and red solution proper shading, 55 gloss, set and finish. This filtered liquid

is a salt solution which can be added to the blue solution; but results are better if red liquid first dries on the hair, then blue likewise permitted to dry thereon to obtain gloss. The yellow when allowed to dry thereon assures 70 finish. A final shampoo with soapy water plus a tablespoon of salt thereafter rinsing with a weak saline solution.

Too much acetic acid causes stripping or cracking or crystallizing. Not enough causes 75 dullness and affects the setting of color. For auburn and red hair use blue and white solution or blue and green solution with the addition of sodium sulphite and alcohol to red solution. By burning the blue vitriol 80 better shades and sets are produced. The burning of the soda insures a better action on red solution. The green solution has a direct action on black and dark brown 85 shades. If the amount of copperas is varied 90 the shades of black and dark brown change accordingly. All other solution ingredients help to prevent bluish shades and prevent copperas from destroying lustre given to hair by blue and red liquids. The green solution 95 in the case of blacks and dark brown and in case of chestnut, medium, light brown, blondes, reds and auburns acts as a substitute for nitrate of silver, sugar of lead and poisonous potassium sets. Cream of tartar or citric acid prevent sediment. All filtering is done in order to remove settling 100 that arise in the treatment of copperas which sediment is commercially useless. I add copperas last in order to replace that which is lost in the treating of ammonia and soda. Zinc oxide removes a certain amount of copper from the blue vitriol that was added to copperas solution, but leaves the other neutralizing ingredients in the blue vitriol 105 solution which otherwise could not be mixed with the copperas solutions under the influence of ammonia. This also leaves a solution which with soda causes an action 110 that calls for another filtering after which the sal ammoniac and the copperas and cream of tartar are used in blue solution to produce blacks and dark browns. In case of blue blacks put both green and blue solution on together so that the ammonia in 115 the blue solution will act immediately upon the green solution. Keep these dyes in cool dark places to prevent spoiling of peroxide in the red solution. In case of deterioration add peroxide. The ammonia in green solution is added to combine the blue vitriol and copperas as in this case also to clear the resulting first filtered liquid. Soda is added 120 not only as a set but as a neutralizer for the blue solution. Tests of the strength of 125 my solutions have all been tried upon the skin of the face. Different amounts are required to obtain different shades. The bases of all colors are, treated copperas, treated blue vitriol and pyrogallic acid, 130

Salt petre used in red solution but may also be added to the blue or the green solution. In case of a real hard wiry fibre of hair special color, instruction should be given. In case of any diseases of the scalp special instructions should be followed in order that the dye may be harmlessly used. To produce drabbish tints an excess amount of ammonia and peroxide should not be added to white fluid. In making the blue solution dissolve soda first in water than add a small amount of ammonia to keep the action from being too strong before adding the burnt blue vitriol. Then add remaining ammonia up to the amount required.

As earlier suggested illimitable eliminable variations of the herein listed ingredients or their chemical family ingredients may be successfully employed in practice. Depending upon the character of the hair to be treated each separate solution may be varied by either subtraction or addition and, moreover, combinations of the various colored solutions may be made, indeed, it is actually possible for me to make a single solution or single bottle hair dye.

Hair dyes are mostly used to color scattered or localized patches of gray hairs which are often prematurely gray because not equally healthy or because not normal. The importance will therefore be realized of matching the adjacent healthy hair which has retained its natural color. One of the primary advantages of my hair dye is that it can be made to penetrate hair which previously marketed dyes failed to penetrate. Manifestly, hard wiry hair is more difficult to penetrate so that one solution or the other must be strengthened and the other solutions to suit in order to compensate their counteracting tendencies. Nitrate of silver in a hair dye is swift in action but I have deliberately avoided its use because it invariably develops weird shades and one of the objects I have held in mind is the attainment of perfection and permanency.

Specifically, the formulas above set forth are those preferred by me after years of experience, but it is not to be understood, and I do not propose to claim, that all of the ingredients are essential.

In the green solution the burnt soda and salamonic acid could on some instances of hair texture be eliminated owing to the presence of another in the blue solution. Moreover, the zinc oxide and cream of tartar are both added merely to improve the commercial appearance. It is even possible to dispense with the green solution entirely if iodide of potassium as a substitute for it is added to the blue solution.

In both blue solutions the citric acid may be eliminated and still obtain all the results desired, this acid being added solely to im-

prove the appearance for commercial purposes. 65

In the red solution neither the acetic acid nor the salt petre is essential. The acetic acid may be eliminated for certain hair textures because the other acid, first specified, 70 is sufficient. The salt petre may be dispensed with in certain instances because it is merely to help the peroxide of hydrogen effect its grip on the blue and the green solutions.

I have stated that it is by no means impossible for me effectively to reduce a hair dye, embodying my invention, to a simple solution for sale in a single bottle. I would iterate that my single solution dye composed of what I deem the essential ingredients 80 will not be as satisfactory. It is inevitably slower in action, less capable of penetration and unlikely to attain the same lustre or fine degrees of shade variations. Nevertheless, I deem it advisable to cite a few examples 85 gathered from actual experience of a single solution dye embodying my invention.

To obtain certain brown shades the blue solution with pyrogallic acid and acetic acid.

For certain red shades the blue solution 90 with the addition of sodium sulphide, pyrogallic acid and acetic acid.

For blacks the green solution with the addition of pyrogallic acid and acetic acid and for some textures of hair iodide of potassium 95 instead of the two acids just named.

I claim:

1. A hair dye composed of 75 grains of a salt of copper, 50 grains of a copper sulphate, 100 2 grams of pyrogallic acid, 5 drams of ammonia, 3/4 of an ounce of peroxide of hydrogen and about 16 1/2 grams of a sulphate of iron held in two solutions with water, the solutions being purposed to be applied successively. 105

2. A hair dye comprising three solutions, the first containing a sulphate of iron, with a salt of copper; the second, an alkali with a salt of copper and the third a mordant with peroxide of hydrogen, said solution intended 110 to be applied to the hair in the order named.

3. A hair dye comprising three solutions the first containing a 1/4 part of a sulphate of iron, a 1/39 part of a copper salt, a 1/32 part of ammonia and water to make about 2 115 ounces, the second solution containing a 1/19 part of an alkali, a 1/13 part of a copper salt, a 1/3 part of ammonia plus water to make another 2 ounces, and the third solution containing 1/32 part of a mordant and a 3/8 120 part of peroxide plus enough water to likewise make 2 ounces.

4. A hair dye comprising three solutions the first containing a 1/4 part of copperas, a 1/39 part of burnt blue vitrol, a 1/32 part 125 of ammonia and water to make about 2 ounces, the second solution containing a 1/19 part of burnt sal soda, a 1/13 part of a burnt

blue vitrol, a 1/13 part of ammonia plus water to make another two ounces, and the third solution containing 1/32 part of pyrogallic acid and a 3/8 part of peroxide plus 5 enough water to again make 2 ounces.

5. A hair dye comprising three solutions aggregating not more than six ounces and including about 1/52 part of a copper sulphate, about 1/30 part of a copper salt dissolved in

water with about 1/9 part of ammonia as a 10 vehicle, 1/100 part of a mordant, a 1/4 part of peroxide and about 1/11 part of a sulphate of iron, to make in all about two fluid ounces.

Signed my me, this 18th day of January, 1919.

IRENE HAMMOND STOLL.
